UNITED STATES PATENT OFFICE

148,430

DESIGN FOR A STRIPPER FORK

Albert L. Luhn, Racine, Wis.

Application July 20, 1946, Serial No. 131,749

Term of patent 7 years

(Cl. D44—29)

To all whom it may concern:

Be it known that I, Albert L. Luhn, a citizen of the United States and resident of Racine, in the county of Racine and State of Wisconsin, have invented a new, original, and ornamental Design for a Stripper Fork, of which the following is a specification, reference being had to the accompanying drawing, forming part thereof.

The figure is a perspective view of the stripper fork showing my new design.

I claim:

The ornamental design for a stripper fork, as shown.

ALBERT L. LUHN.
